Primary Examiner — Michael A Pratt(74) *Attorney, Agent, or Firm* — Christensen, Fonder, Dardi & Herbert PLLC(57) **CLAIM**

The ornamental design for a cartridge with an enhanced ball round, as shown and described.

DESCRIPTION

FIG. 1 is a front side elevational view of a cartridge with an enhanced ball round according to an embodiment of the invention. The view from the opposite side being identical thereto.

FIG. 2 is a front side perspective view of the cartridge with an enhanced ball round of FIG. 1. The view from the opposite side being identical thereto.

FIG. 3 is a front side perspective view of the cartridge with an enhanced ball round of FIG. 1. The view from the opposite side being identical thereto.

FIG. 4 is a top plan view of the cartridge with an enhanced ball round of FIG. 1; and,

FIG. 5 is a cross sectional view of the forward portion of the cartridge with an enhanced ball round of FIG. 1 in order to illustrate clearly the exteriorly exposed shape of the forward portion. Only the exteriorly exposed surfaces are claimed. The internal features are not claimed.
